ATTORNEY

UNITED STATES PATENT OFFICE

CHARLES E. TUMMINELLO, OF PITTSBURGH, PENNSYLVANIA, ASSIGNEE OF ONE-FOURTH TO SAMUEL A. GREENBERG AND ONE-FOURTH TO HARRY K. ANGEL, BOTH OF PITTSBURGH, PENNSYLVANIA

SELF-SORTING CARD FILE

Application filed July 30, 1930. Serial No. 471,784.

This invention relates to a card holder, the general object of the invention being to provide means for raising certain cards in the holder so that the same will be separated from the other cards, the invention being more particularly designed for use with cards which are filed according to dates and acts to sort all cards of a due date without necessitating the removal of the cards from the holder.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a top plan view of the invention.

Figure 2 is a section on line 2—2 of Figure 1.

Figure 3 is a section on line 3—3 of Figure 1.

Figure 4 is a view of the shaft.

Figure 5 is a view of a blank from which the hollow slotted member is formed.

Figure 6 is view of one of the cards.

In these drawings, the numeral 1 indicates the holder for the cards and 2 indicates the follower plate which is held in adjusted position by the spring member 3 attached to the rear face of the follower and having its end portions engaging the rack bars 4 inserted in grooves in the inner side walls of the holder. By pressing the looped ends 5 of the spring member toward each other, the teeth-forming ends of the member will be free of the rack bars so that the member can be moved rearwardly. It is simply necessary to push the member forwardly to hold the cards in proper position in the holder.

Each card B is formed with the depending parts or legs 6 and a plurality of longitudinally extending slats 7 are supported

for vertical movement in the ends of the casing by having their ends extending into the recesses 8 formed in the inner walls of the end pieces. The legs of the cards rest on these slats and it will be understood that the legs are arranged at different points on the lower edges of the cards so that the legs will rest on different slats. In other words, all the cards bearing the same date, for instance, have their legs located at the same points so that they will engage the same slats, but cards bearing different dates will have their legs arranged to engage other slats. The drawings show the cards each provided with a pair of legs for engaging two of the slats so that these two slats must be moved in unison to raise a card or cards, but it will be understood that I do not wish to be limited in this respect.

A tubular member 8' passes transversely through the center of the casing under the slats and this member is preferably formed of a blank 9 of metal having the parallel slots 10 in one edge thereof, this blank being rolled to form the tubular member 8', with the ends of the tongues formed by the slots 10 spaced from the other side edge of the blank so as to form a longitudinally extending slot 11. The ends of the tubular member are fastened to the walls of the holes in the sides of the casing, as shown at 12. A shaft 13 passes through the tubular member and has a nut 14 at one end for preventing the shaft from being entirely withdrawn from the tubular member and a handle 15 at its other end so that the shaft can be moved longitudinally and also turned. A pair of projections 16 extend laterally from the shaft.

From the foregoing it will be seen that the shaft can be moved longitudinally while the projections 16 are in the slot 11 to position the projections under the slats upon which the cards which are to be raised rest and the shaft is provided with the graduations 17 for facilitating the proper adjustment thereof. Then the shaft is turned so that the projections will pass through two of the slots 10 and thus contact with the lower edges of two of the slats and raise the

same, as shown in Figure 3. Thus the cards, the legs of which rest upon these slats, will be raised, as shown in Figures 2 and 3. Thus these cards are separated or sorted 5 from the other cards.

It is thought from the foregoing description that the advantages and novel features of the invention will be readily apparent.

It is to be understood that changes may 10 be made in the construction and in the combination and arrangement of the several parts, provided that such changes fall within the scope of the appended claims.

What I claim is:—

15 1. A device of the class described comprising a card-holding casing, a plurality of slats therein, cards having their lower edges formed with projections resting upon the slats, the cards being arranged in sets with 20 the projections of one set in a different location from the projections of the other sets whereby the different sets of cards will engage different slats, selective means for raising the slats which support any desired set 25 of cards, such means consisting of a shaft rotatably and slidably arranged in the casing under the slats and projections on the shaft for engaging the lower edges of the slats to raise the same when the shaft is 30 turned.

2. A device of the class described comprising a card-holding casing, a plurality of slats therein, cards having their lower edges formed with projections resting upon the 35 slats, the cards being arranged in sets with the projections of one set in a different location from the projections of the other sets whereby the different sets of cards will engage different slats, selective means for raising 40 the slats which support any desired set of cards, such means consisting of a shaft rotatably and slidably arranged in the casing under the slats, projections on the shaft for engaging the lower edges of the slats to 45 raise the same when the shaft is turned, and 50 a tubular member through which the shaft passes, said tubular member having a longitudinal slot and transverse slots opening into the longitudinal slot whereby the shaft can 55 be moved longitudinally with the projections thereon in the longitudinal slot and then turned to cause the projections to enter certain of the other slots.

In testimony whereof I affix my signature.

CHARLES E. TUMMINELLO.
